UNITED STATES PATENT OFFICE

WILLIAM LEWIS, OF UTICA, NEW YORK

CONVERTIBLE SINGLE OR DOUBLE BED

Application filed September 2, 1927. Serial No. 217,115.

This invention relates to a convertible single and double bed involving the use of separate mattress-supporting frames, one of which is slidable horizontally upon the other, and separate spring mattresses for said frames, one of which is hingedly connected to the main frame to swing from the extended sliding frame to a position above the other mattress and vice versa.

- 10 The main object is to provide a bed of this character in which the sliding frame maintains approximately the same level slightly below the other frame in both extreme positions of adjustment and to enable the mattress for the sliding frame to be moved independently thereof from an operative position on the sliding frame to an inverted position in superposed relation to the other mattress to form a single or double bed and
- 15 to enable the coverings for both mattresses to be concealed between them when the mattress for the sliding frame is adjusted over and upon the other mattress to form a single bed or couch.
- 20 25 The object in making the mattresses for both frames separate from each other is to maintain the resiliency of each throughout its area without affecting the resiliency of the other mattress when the frames are relatively adjusted for use as a double or twin bed and also to obtain the combined resiliency of both mattresses when placed one upon the other for use as a single bed or couch.
- 30 35 A further object is to make the mattresses of unequal resiliency so that one may be used for lighter weights and the other for heavier weights.

Other objects and uses relating to specific parts of the bed will be brought out in the following description.

In the drawings:—

Figure 1 is a perspective view of a convertible single and double bed embodying the various features of my invention adjusted for use as a single bed or couch, the dotted lines indicating the sliding frame as extended for use.

Figure 2 is an enlarged transverse vertical sectional view taken in the plane of line

2—2, Figure 1, the dotted lines indicating the sliding frame with the mattress thereon adjusted for use as a twin or double bed.

Figure 3 is an enlarged detail sectional view taken in the plane of line 3—3, Figure 2.

Figure 4 is an enlarged longitudinal vertical sectional view, partly broken away, taken on line 4—4, Figure 1.

Figure 5 is an enlarged detail sectional view of a portion of one of the posts and one of the adjacent supporting straps for the mattress of the sliding frame showing the sliding pivotal connection between said mattress and the main frame for the other mattress, the posts being, in this instance, in the form of square tubes.

Figure 6 is an enlarged horizontal sectional view through the lower right hand portion of the bed taken in the plane of line 6—6 Figure 4, except that the sliding frame is drawn outwardly to the limit of its outward movement and portions of both frames are broken away.

Figure 7 is an enlarged perspective view of the lower right hand corner of the main frame shown in Figure 4 showing more particularly the adjacent guide rails for the sliding frame and one of the attaching straps for the mattress for said sliding frame, the corner posts being shown as square tubes.

As illustrated, this bed comprises a main frame —1—, a supporting frame —2—, and separate spring mattresses —3— and —4— together with suitable connections between the mattress —4— and frame —1— to permit said mattress to be moved to and from a position in superposed relation to the mattress —3— without disconnecting it from said frame as will be hereinafter more fully explained.

The main frame —1— is substantially rectangular in top plane and comprises opposite parallel side rails —5— and opposite end rails —6— together with suitable corner posts —7— all of which are preferably made of angle irons rigidly secured together at the corners.

The side rails —5— are arranged with

their angles at the lower outer edges of the frame so that two of the flanges will be disposed in vertical planes while the remaining flanges will be disposed in a horizontal plane 5 extending inwardly from the first named flanges.

The end flanges are arranged with their angles at the upper outer edges of the ends of the frame with two of the flanges disposed in vertical planes and the remaining flanges 10 projecting downwardly from the upper edges of the horizontal flanges which overlap upon the horizontal flanges of the lengthwise rails and are riveted or otherwise rigidly secured 15 to the underside thereof.

The posts —7— are arranged with their angles at the corners so that the overlapping portions of the side and end rails are seated against the inner faces of the flanges of the 20 posts with their upright flanges riveted or otherwise secured to said posts some distance from the lower ends thereof to form a rigid unitary frame structure as shown more clearly in Figures 3 and 7.

25 The lower horizontal flanges of the side rails —5— are connected by a series of slats —8— of spring metal arranged in uniformly spaced parallel relation lengthwise of the end rails and riveted or otherwise secured there- 30 to.

The upper flanges of the end rails —6— are connected by lengthwise slats —8— of 35 spring metal arranged in uniformly spaced parallel relation transversally of the frame and preferably extending under the cross slats —8—, said slats being riveted or otherwise secured to the end rails and are also riveted or otherwise secured to each other at their intersections or crossings to assist in 40 imparting rigidity to the main frame and also in supporting the mattress —3—. The end faces of lengthwise rails —5— are disposed in the same vertical planes as the outer faces of the outer flanges of the end rails 45 —6— while the end faces of the end rails are disposed in substantially the same plane as the outer faces of the side rails so that the corners of the frame —1— may fit snugly in the angles of the post —7— as shown 50 more clearly in Figure 4 thus permitting relatively broad bearings for the post and frame and when riveted together in the manner described establishes rigid connection between the posts and frame.

55 As shown in Figures 1 to 6 inclusive suitable brackets —9— are riveted or otherwise secured to the inner faces of corner posts —7— to project inwardly toward each other from the ends of the frame in planes just 60 below the end rails —6— for receiving and supporting a pair of guide rails —10— which are preferably made of angle irons having upright flanges riveted or otherwise secured to the inner faces of brackets —9— and other flanges extending inwardly from the before

named flanges to form supports for the supplemental frame —2— presently described.

This supplemental frame —2— is also rectangular and of approximately the same 70 length and width as the main frame —1— and is supported at its ends upon the guide rails —10— for forward and rearward sliding movement to and from a position directly under main frame —1— and also to and from a position mainly at the front side of main frame, the guide rails —10— being parallel 75 and preferably made in the form of angle irons arranged so that two of the flanges will be in a horizontal plane projecting toward each other from the remaining flanges as shown in Figure 4.

80 As illustrated this supplemental or sliding frame —2— comprises opposite front and rear parallel lengthwise rails —11— and —12— and opposite end rails —13— riveted or otherwise secured together in overlapping relation at the corners to form a rigid unitary structure.

These rails —11—, —12—, and —13— are 85 preferably made of angle irons the front and rear rails being arranged with their outermost flanges disposed in vertical planes and their remaining flanges projecting inwardly in horizontal planes but in reverse order while the end rails —13— are preferably arranged with their outermost flanges disposed in vertical planes and their innermost flanges projecting toward each other in horizontal planes.

90 The horizontal flanges of the side rails —11— and —12— are disposed in substantially the same horizontal plane but the vertical flanges of the front rail extends upwardly to form a limiting stop cooperating 95 with the front rail of the main frame for limiting the innerward sliding movement of the supplemental or sliding frame while the vertical flanges of the rear rail —12— projecting downwardly from the horizontal flanges to form a limiting stop cooperating 100 with stop pins —14— on the front ends of the guide rails —10— as shown in Figures 105 6 and 7 for limiting the outward movement of the sliding frame relatively to the main frame.

110 The supplemental frame like the main frame is provided with resilient bottom comprising parallel lengthwise slats —15— and parallel cross slats —15— of spring metal riveted or otherwise secured to the lengthwise slats at the crossing, said slats having their ends riveted or otherwise secured to the end rails and to the side rails.

115 The front rail —11— of the sliding frame —2— is provided near its ends with downwardly extending legs —17— having their upper ends riveted or otherwise secured to said front rail and their lower ends provided with casters —18— adapted to roll 120 upon the floor to cooperate with the guide 125 rails —10—.

rails —10— in holding the sliding frame in a substantially horizontal plane when adjusted for use.

The mattress —3— is of substantially the same length and breadth as the slat bottom of said frame between the upright flanges of the lengthwise side rails —5— which serve to hold the mattress against forward and rearward displacement and permit it to be readily removed from the frame when desired by upward displacement.

As illustrated this mattress —3— comprises a pair of similar rectangular wire frames —19— and —19'— extending around the marginal edges of the mattress and having their opposite sides and opposite ends connected by a system of lengthwise and transverse wires crossing each other at right angles in spaced relation to form resilient supports for a system of coiled springs —20—.

The construction of the mattress —4— is somewhat similar to the mattress —3— in that it comprises a pair of rectangular marginal wire frames —23— and —24— having their lengthwise sides and ends connected by cross wires forming resilient supports for a system of coiled springs —25— which are interposed between the cross wires of the lower and upper frames —23— and —24— yieldingly holding them in normally spaced parallel relation.

It will be noted, however, that the ends of the frames —23— and —24— are connected near one of their lengthwise sides by vertical braces —26— of sheet metal having their lower and upper ends provided with eyes —26'— which are looped around the adjacent portions of frames —23— and —24— to hold those portions of the frames in fixed spaced relation and also to form suitable support for a pair of hinge straps —28—.

These hinge straps —28— are riveted or otherwise secured to the intermediate portions of the braces —26— at opposite ends of and between the frames —23— and —24— to extend slightly beyond the corresponding edge of the mattress for receiving and supporting a pair of pivotal studs —29— carrying suitable rollers —30— which in turn are movable in vertical guides —31— on the front side of the main frame —1— near the front corner thereof as shown more clearly in Figures 2, 3 and 5.

When the posts —7— are made of angle irons the guides —31— will also be made of angle irons riveted or otherwise secured to the inner faces of the adjacent portions of the front posts —7— and provided with vertical slots for receiving the rollers —30— on the studs —29— thereby establishing sliding pivotal connection between the mattress —4— and frame —1—.

In some instances the posts may be made

of square tubes in which case the guide slot —31— may be formed in a separate U-shaped strap or bracket —32— having its ends secured to the face of the square post —7— as shown in Figure 5 or in some instances the guide slots —31— may be formed directly in the inner walls of the square posts —7— as shown in Figure 7.

In each of these modifications the straps —28— and studs —29— together with the slotted guides constitute vertically slidable pivotal connections between the mattress —4— and front side of frame —1— to permit said mattress to move vertically and also to swing from a horizontal position directly over the mattress —3— to an inverted horizontal position over and upon the sliding frame —2— when the latter is extended for use.

What I claim is:

In a convertible single or double bed, the combination of a main frame having relatively fixed corner posts, a mattress mounted on the main frame, and a supplemental frame slideable on the main frame from a position beneath the mattress to a position mainly at one side thereof and vice versa, the corner posts adjacent said side of the main frame being provided with vertical slots wholly above the supplemental frame, and an additional mattress provided with pivotal pins slideable vertically in said slots and having pivotal connection therewith to permit the additional mattress to be moved vertically relatively to and independently of the first named mattress to a position at one side thereof directly over the supplemental frame when the latter is extended for use.

In witness whereof I have hereunto set my hand this 22d day of August, 1927.

WILLIAM LEWIS.
